UNITED STATES PATENT OFFICE.

HARRY H. WIGGLESWORTH AND HAROLD O. KAUFMANN, OF PHILADELPHIA, PENNSYLVANIA, ASSIGNORS TO THE PHILADELPHIA DRYING MACHINERY COMPANY, OF PHILADELPHIA, PENNSYLVANIA, A CORPORATION OF PENNSYLVANIA.

DRYING MACHINE.

Application filed April 10, 1922. Serial No. 550,956.

To all whom it may concern:

Be it known that we, HARRY H. WIGGLESWORTH and HAROLD O. KAUFMANN, citizens of the United States, residing at Philadelphia, county of Philadelphia, and State of Pennsylvania, have invented certain new and useful Improvements in Drying Machines, of which the following is a specification, reference being had to the accompanying drawings.

Our invention relates generally to drying machines, and more especially to machines of a type useful in drying textile manufactures capable of being stretched upon thin, flat shaping forms, such, for example, as hosiery and the like.

Among the objects of our invention are to secure, in machines of the class specified, greater structural compactness with consequent saving of space necessary for their accommodation; higher efficiency in operation than heretofore attainable; and to effect greater economy in cost of operation through minimization of manual labor incidental to such operation.

Other objects and attendant advantages will become readily apparent from the detailed description of a typical embodiment of our invention which follows.

In the accompanying drawings Fig. I is a perspective view of a drying machine conveniently embodying our invention, with one side panel removed to disclose the interior.

Fig. II is a side elevation of the same.

Fig. III is a view of the machine in top plan.

Fig. IV is an illustration, in plan, of a specially designed sprocket chain forming a part of the conveyor whereby the articles to be dried are carried through the machine, portions of the chain being shown in section at two different planes so that its construction may be more readily understood.

Figs. V and VI are perspective views of the two main or side members which constitute the links of the chain aforesaid.

Fig. VII is a perspective view of one of the antifriction rollers associated with the chain links.

Fig. VIII is a view of the machine in transverse section taken on the line VIII—VIII of Fig. III.

Fig. IX is a fragmentary view in top plan

of the discharging end of the drying conveyor illustrating a preferred form of dry- 55 ing board dislodging means.

Fig. X is a fragmentary view in side elevation of the parts shown in the immediately preceding figure.

Fig. XI is a view of the machine in longitudinal section on a plane extending 60 through the drying chamber.

Fig. XII is a fragmentary view in longitudinal section of a series of board returning conveyors, showing the receiving 65 ends.

Fig. XIII is a view in longitudinal section of the discharge end of one of the board returning conveyors.

Fig. XIV is a detail view in section taken 70 on the line XIV—XIV of Fig. X.

Fig. XV is a detail view in transverse section of the drying conveyor apron illustrating a modified form of air current deflector; and 75

Fig. XVI is a fragmentary view in plan of a portion of the drying conveyor illustrating a modified form of drying board dislodging means.

The structure herein represented as typi- 80 cal of our invention, comprises a fireproof enclosure 1 consisting of a skeleton frame 2 preferably of structural steel and a number of enclosing panels 3—3 removably hung to said frame. The enclosure 1, as clearly 85 shown in Figs. I and VIII, is subdivided, by means of a longitudinally extending partition 5, into a drying chamber 6 and a heating chamber 7. The latter of these

chambers serves to accommodate suitable 90 heating means herein shown as a bank of steam coils 8 for heating the air as it is circulated through the enclosure in a manner to be presently described. The machine has a peaked roof portion 10 which is arched 95 across both the heating chamber and the greater portion of the drying chamber and also subdivided by the longitudinal partition 5 previously mentioned. At a point

preferably intermediate its length, and in that part within the roof portion 10, the partition 5 has a shrouded circular opening 11

within which revolves a fan 12. Said fan is secured to a shaft 13 journaled at the exterior in bearings 14, 14, and adapted to be 100

driven by means of a pulley 15 coordinated,

55

75

80

85

90

95

100

105

through a belt connection (not shown) with any suitable source of power. Referring again to Fig. VIII, it will be noted that the lower edge of the partition 5 terminates short of the floor of the enclosure so as to afford a passage along the entire length of the structure, for communication of the drying chamber 6 and the heating chamber 7. Thus, under the propulsion of the fan 12, 10 the air is circulated laterally of the enclosure as indicated by the arrows in Fig. VIII in a direction downward through the drying chamber 6, thence through the space beneath the partition 5 and upward through the 15 heating chamber. If desired, or in case it should be required in the treatment of certain materials, the rotation of the fan may obviously be reversed to circulate the air in a direction opposite to that indicated.

20 The drying chamber 6 is traversed longitudinally by a conveyor 19 which comprises a sprocket chain 20 and a series of parallelly extending bands 21, 22, 23, 24, moving synchronously with the chain and 25 spaced at various lateral distances therefrom. Said bands are preferably attached to an endless foraminous apron 25 which extends to the exterior through suitable openings in opposite ends of the enclosure 30 and is supported upon drums 26, 27 whose shafts 28-28 are journaled for rotation in bearings 29, 29 one of which is movable to permit tightening of the chain and secured to extended portions of the skeleton frame 35 2. The sprockets 30, 30 upon which the chain 20 runs, are secured to the shafts 28, 28 adjacent one end of the drums 26, 27 as clearly shown in Figs. I and III. The shaft 28 of the drum 27 at the discharge end of 40 the machine (at the right of Fig. I) is positively driven by means of gearing concealed within a casing 31 and coordinated through a shaft 32 with similar gearing concealed in a casing 33, the latter gearing being in 45 turn actuated by a shaft 34 carrying a pulley 35. The edges of the apron 25 along the upper stretch are preferably run in grooves provided in supporting ledges 36 which in turn are supported upon the walls 50 of the machine, as shown in Fig. XV.

55 As previously stated herein, the machine of our invention is especially adapted for drying articles, such for example as stockings, and the like, capable of being stretched upon thin, flat, shaping forms. In order to effect economy of the space required for a machine of this character, the forms are, in the present instance, carried through the 60 drying chamber while supported on edge in uniformly spaced relation and in horizontal position transversely of the conveyor. In order that this may be accomplished, the companion side members 37, 38 which constitute the links of the sprocket chain 20, 65 (see Figs. V and VI) are formed with spaced upstanding projections 39, 39. These side members, as clearly shown, are made as rights and lefts and have, at one end, complementary, inwardly projecting trunnions 40, 40 which, when assembled in 70 the chain, abut along the center line of the latter, (see Fig. IV) and jointly serve to support antifriction rollers such as shown in perspective at 41 in Fig. VII. The trunnions 40, 40 are axially bored as at 42 for 75 reception of pins 43 which are headed as best seen in Fig. IV to hold the parts of the chain links together. The lugs 44 from which the trunnions 40, 40 extend are offset somewhat from the general plane of the 80 link members 37, 38 so as to accommodate the ears 45, 45 of adjacent links. By this arrangement, a continuous double row of 85 projections 39 is afforded along one edge of the conveyor. The aligned pairs of adjacent projections of the respective rows are cooperative in engaging between them ends of the flat forms preferably those which protrude beyond the stocking tops, so that the fabric may not be injured, see Fig. VIII, 90 and thus not only sustain the forms on their edges, but hold them separated and against displacement in horizontal position laterally or transversely of the conveyor. The bands 21, 22, 23, 24 are so spaced upon the foraminous apron 25 with relation to the chain 20 as to be at the proper distances to support, with minimum contact, either the heel or toe ends of the foot portion (preferably 95 the latter as herein shown) of forms of various sizes. In practice the said bands are preferably made of a suitable soft absorbent material such as felt so as to preclude possible injury to the stocking fabric at the point of contact, and to be capable of absorbing moisture imparted thereto by virtue of such contact. Thus with a machine of our invention it will be seen that stockings of various sizes can be dried at one time without regard to order or sequence, 100 thereby greatly enhancing the efficiency of the machine in this respect.

105 In its traverse through the machine, the conveyor is guided between side rails 50, 50 secured to the skeleton frame 2 and the upper stretch of the apron 25 may be sustained against sagging under load by suitable means such for example as the supporting ledges 36 mentioned above. The lower or return run, of the conveyor is held 110 against sagging by means of spaced rollers 51 supported by the rails 50 as shown in Fig. VIII.

115 The apron 25 by reason of being perforated or foraminated, will offer but very little resistance to the movement of the air between and about the series of forms carried by the conveyor so that the time period necessary for complete and thorough drying is appreciably shortened. The channel- 120

125 130

ing of the air resulting from the arrangement of the forms on the conveyor also assists materially in reducing the time of drying to a minimum.

5 The conveyor is loaded at the right hand end of the machine as considered in Fig. III, by a number of operators who are stationed along the conveyor. Adjacent this end of the machine a number of tables 55 10 are provided upon which forms may be supported in an upright position while the stockings are stretched thereon by the operative preparatory to being placed on the conveyor. After being properly mounted 15 on the conveyor and engaged for support on edge by the upstanding projections 39, 39 of the sprocket chain 20, the charged forms are progressed at a comparatively slow but uniform rate of speed through the drying 20 chamber 6 and thoroughly subjected to the circulating air as already noted.

In order to effect automatic removal of the forms from engagement between the sustaining projections 39 of the sprocket chain 25 20 after the completion of the drying operation, we have provided, at the discharge end of the machine, (see Figs. IX and X) and adjacent said chain, a stationary inclined cam 60 which engages the extremities of the 30 forms from beneath and gradually lifts them from between said projections. This action is clearly illustrated in Fig. X. As the forms are thus raised, they are intercepted by a stationary stop 61 which engages them near their upper edges and tilts them 35 rearwardly so as to fall flat with the stocking toes pointing forwardly. As a consequence the forms are discharged, by further movement of the conveyor, in a definite pre- 40 ordered position upon a receiving table 59 where another operative removes the dried stockings.

The forms are now to be returned to the operators at the loading end of the machine 45 for reuse. This transferal is accomplished by means of a plurality of conveyors 62, 63 and 64, arranged parallel in superposed relation at the side of the machine at which the loading operators are stationed. The 50 uppermost conveyor is the shortest and the lowermost the longest, the other conveyor being of an intermediate length so that the loading ends of these conveyors may be disposed in step relation adjacent the discharging end of the drying conveyor as shown in Fig. XII. The discharging ends of said 55 form conveyors are relatively spaced horizontally to a greater extent so that each conveyor may discharge upon its corresponding platform of a series of three indicated at 60 65. To facilitate entry of the forms upon and between these conveyors, the loading end of each is shrouded by means of a sheet metal shield 66; and the discharge of the 65 forms from the conveyors to the platforms

65 is ensured by providing a roller 67, one at the discharge end of each conveyor, and driven from its respective conveyor in the same direction but at a higher rate of speed, preferably through the medium of a belt 70 and pulley connection 68 as shown in Fig. XIII. The loading end of each form conveyor is driven through the medium of a sprocket wheel, indicated with respect to the several conveyors at 69, 70 and 71, as 75 shown in Fig. II. The intermediate sprocket 70 is driven by and operates in unison with a relatively large spur gear 72 which meshes with a pinion 73 the latter in turn rotating with a pulley 74. Said pulley 74 is 80 preferably belt driven from the above mentioned shaft 34 through the medium of a pulley 75 carried by the latter. The intermediate portions of the form conveyors are run through a housing 76, shown in Fig. 85 VIII, which receives heat by radiation from the heating element 8 so that the forms are dried and warmed prior to the stretching of the wet hosiery thereon. The conveyor apron 25 may be retained under proper tension by the provision of a tightening or slack absorbing arrangement as shown in Fig. XI and consisting of a roller 77 beneath which the lower stretch of the apron travels in contact therewith, said roller 77 being 90 supported at one or both ends by means of one or two arms 78, as the case may be, the roller being shiftable to place the apron under tension by virtue of set screws 79 engaging said arm or arms. The loading extremity of the drying conveyor may be enclosed, if desired, within a suitable housing 95 100 105 110 115 120 125 130

To ensure the travel of the air current in the manner described against the possibility of its diversion owing to the movement of the forms through the entering and leaving end of the chamber we may provide at each of said ends a vestibule in the form of 110 housings 81, the portals of which are closed by means of portières of hanging felt strips, or the like, 82 which are parted and moved aside by the forms when the latter enter and leave the said vestibules.

When half hose or children's stockings are to be dried shorter forms are used which do not extend from edge to edge of the drying conveyor. Consequently there is a tendency for the air current to pass through the apron beyond the toe ends of the forms instead of between the forms, as the air current should be directed, and as a result the removal of moisture from the hosiery is not complete or accomplished as quickly as it should be. This contingency is avoided by a means shown in Fig. VIII and which consists of a plurality of depending slats 83 which are hinged from any suitable stationary support and located beneath the upper stretch of the apron at a point adjacent the outer edge. 130

A rod 84 is slidably mounted above the slats and is provided at suitably spaced intervals with lugs 85 which are designed to engage pins 86 of which each slat is provided with one. A spring 87 is provided to urge the rod toward a non-operative position, while a flexible connection 88 to the rod runs over a pulley and is connected to a lever 89 cooperating with a segment and locking arrangement. By rocking the lever the lugs 85 will successively engage the pins 86 of the slats 83 in the order of the outermost slat first, moving said slats successively upward against the apron to form a baffle and thereby ensure the passage of the air current between the hosiery forms. One or more of the slats may thus be raised according to the length of the hosiery forms used.

The baffling of the air current for short forms may also be accomplished in the manner shown in Fig. XV wherein 90 indicates a plurality of leaves, hingedly connected in edge to edge relation, an end leaf being hinged to the outermost rail 37, so that the arrangement may be unfolded to dispose one or more leaf sections above the apron, thus forming a baffle. The entire arrangement may be folded back when not in use as shown in dotted lines. To support the upper stretch of the main conveyor apron 19 a plurality of longitudinal slats 91 are arranged therebeneath and preferably directly below and in contiguous relation to the bands 21-24. The lower stretch of the form carrying chain 20 is prevented from sagging unduly by providing a plate 92 mounted edgewise and upon which the chain runs, the fingers 39 being carried, one series at each side thereof.

A slightly modified arrangement for dislodging the forms at the discharging end of the drying conveyor is shown in Fig. XVI wherein a stationary cam plate 93 is arranged in a horizontal position to be engaged by the ends of the forms so as to shift said forms transversely and horizontally from between the holding fingers 39. After such disengagement the forms may be knocked over, all in the same direction by engagement against the stop member 61 described above.

It will be seen that the operating intervals of the several elements of the machine are so coordinated that no waste of time ensues by one operator waiting upon another to catch up in work. Thus, since it requires three times as long to apply a piece of hosiery to a form as it does to remove the piece we have provided facilities for three loading operators who are required to keep the conveyor filled to capacity, which may be unloaded by one operator.

Other advantages will readily occur to those familiar with the art to which this invention appertains.

Having thus described our invention, we claim:

1. A drying machine comprising a drying chamber; a traversing conveyor for supporting, on edge, a series of flat forms with the articles being dried stretched thereon; and means for engaging the forms from beneath to effect their discharge in a definite flat position from the machine after the conveyor has completed its circuit therethrough. 75

2. A drying machine comprising a drying chamber; a traversing conveyor for supporting, transversely thereof and on edge, flat forms with the articles being dried stretched thereon; and means for engaging the forms from beneath and ordering discharge of said forms from the machine in a definite flat position after the conveyor has completed its circuit therethrough. 80

3. A drying machine comprising a drying chamber; a traversing conveyor having a series of spaced, upstanding projections capable of sustaining, on edge between them, flat forms with the articles being dried stretched thereon; and elevating means 85 whereby the forms are automatically disengaged from between the projections of the conveyor for discharge from the machine when the conveyor has completed its circuit therethrough. 90

4. A drying machine comprising a drying chamber; a traversing conveyor having a series of spaced upstanding projections capable of sustaining, on edge between them, flat forms with the articles being dried stretched thereon; and a stationary incline cam for engaging the forms from beneath to effect their release from between said projections for discharge from the machine when the conveyor has completed its circuit 105 therethrough.

5. A drying machine comprising a drying chamber; a traversing conveyor having a series of spaced, upstanding projections capable of sustaining, on edge between them, flat forms with the articles being dried stretched thereon; means for engaging the forms from beneath to effect their release from between the projections of the conveyor; and cooperative means for tilting the forms uniformly in one direction for discharge from the machine in a definite flat position. 110 115

6. A drying machine comprising a drying chamber; a traversing conveyor having a series of spaced upstanding projections capable of sustaining on edge between them, flat forms with the articles being dried stretched thereon; a stationary inclined cam for engaging the forms from beneath to effect their release from between said projections after the conveyor has completed its circuit through the machine; and a cooperative stationary stop for engaging the forms near their top edges to tilt them uniformly 120 125 130

- in one direction for discharge from the machine in a definite flat position.
7. A drying machine comprising a drying chamber; and a traversing conveyor with means for engaging flat forms with articles being dried stretched thereon at one end only to sustain them on edge and in spaced relations for support in a horizontal position transversely of the conveyor.
- 10 8. A drying machine comprising a drying chamber; and a traversing conveyor having along one of its edges a series of spaced, upstanding projections between which flat forms with the articles being dried stretched thereon are engaged at one end only and sustained on edge for support in a horizontal position transversely of said conveyor.
- 15 9. A drying machine comprising a drying chamber; a traversing conveyor for supporting a series of flat forms with stockings or the like stretched thereon, said conveyor having along one of its longitudinal edges, a series of spaced upstanding projections adapted to engage between them, those ends 20 of the forms which protrude beyond the stocking tops to sustain said forms on edge for support in a horizontal position transversely of the conveyor.
- 25 10. A drying machine comprising a drying chamber; and a traversing conveyor having a double row of spaced, upstanding projections, aligned pairs of fingers of the respective rows serving to engage between them, flat forms with the articles being dried stretched thereon, for support on edge and in a horizontal position transversely of the conveyor.
- 30 11. A drying machine including a drying chamber; and a traversing conveyor comprising a pair of spaced, synchronously moving bands for supporting opposite ends of flat forms with the articles being dried stretched thereon, one of said bands having means for sustaining the forms on edge.
- 35 40 12. A drying machine comprising a drying chamber; and a traversing conveying means including a series of spaced, synchronously moving bands adapted for co-operation in pairs in supporting opposite ends of flat forms of different lengths with the articles being dried stretched thereon.
- 45 13. A drying machine comprising a drying chamber; and a traversing conveying means for carrying transversely thereof a series of flat forms with the articles being dried stretched thereon, said conveying means including a chain with upstanding projections for sustaining and supporting on edge between them, one end of flat forms 50 with the articles being dried stretched thereon; and a companion band running parallel to, and moving synchronously with the chain for supporting the opposite ends of the forms.
- 55 60 65 14. A drying machine comprising a chamber within which a suitable drying medium is constantly circulated; a conveyor apron of foraminous material, capable of permitting ready passage of the drying medium therethrough; traversing said chamber; and means for sustaining flat forms, with the articles being dried stretched thereon on edge and in spaced relation for support in a horizontal position on said conveyor apron.
- 70 75 15. A drying machine comprising a chamber within which a suitable drying medium is constantly circulated, a conveyor apron of foraminous material, capable of permitting ready passage of the drying medium therethrough, traversing the chamber, means along one edge of the conveyor for engaging the ends of forms protruding beyond the tops of stockings stretched thereon to sustain them on edge during conveyance; and a comparatively narrow longitudinally extending band of absorbent material attached to the conveyor apron at a distance from the edge aforesaid for supporting the foot ends of said forms.
- 80 85 90 95 100 105 110 115 120 125 130 135 140 145 150 155 160 165 170 175 180 185 190 195 198 200 205 210 215 220 225 230 235 240 245 250 255 260 265 270 275 280 285 290 295 298 300 305 310 315 320 325 330 335 340 345 350 355 360 365 370 375 380 385 390 395 398 400 405 410 415 420 425 430 435 440 445 450 455 460 465 470 475 480 485 490 495 498 500 505 510 515 520 525 530 535 540 545 550 555 560 565 570 575 580 585 590 595 598 600 605 610 615 620 625 630 635 640 645 650 655 660 665 670 675 680 685 690 695 698 700 705 710 715 720 725 730 735 740 745 750 755 760 765 770 775 780 785 790 795 798 800 805 810 815 820 825 830 835 840 845 850 855 860 865 870 875 880 885 890 895 898 900 905 910 915 920 925 930 935 940 945 950 955 960 965 970 975 980 985 990 995 998 1000

and between the forms, and means to cover a portion of the conveyor when shorter forms are used so as to direct the air current between said short forms.

- 5 20. A drying machine, comprising a conveyor, a drying chamber through which the conveyor passes, means to support hosiery forms on the conveyor so that when the latter is filled with forms of maximum 10 length the entire operating surface of the conveyor will be filled, means to direct a current of air through the conveyor and between the forms, a plurality of means each designed to cover a portion of the conveyor when shorter forms are used, and means to move the units of said covering 15 means successively to covering position to cause one, or several, or all of said units

to cover the conveyor according to the length of forms used. 20

21. A drying machine, comprising a drying chamber, means to convey hosiery forms set on edge through the chamber, a heating element in the chamber, and means to create a continuous air current passing between the forms, to the heating element and again to the forms. 25

In testimony whereof, we have hereunto signed our names at Philadelphia, Pennsylvania, this seventh day of April, 1922.

HARRY H. WIGGLESWORTH.
